UNITED STATES PATENT OFFICE.

GEORGE A. BURNHAM, OF SAUGUS, MASSACHUSETTS, ASSIGNOR TO SEARS B. CONDIT,
OF BROOKLINE, MASSACHUSETTS.

ELECTRIC SWITCH.

Application filed June 3, 1920. Serial No. 386,347.

To all whom it may concern:

Be it known that I, GEORGE A. BURNHAM, a citizen of the United States, residing at Saugus, in the county of Essex and State of Massachusetts, have invented an Improvement in Electric Switches, of which the following is a specification.

This invention relates to an oil immersed electric switch adapted to control and interrupt circuits carrying relatively high values of current and is of the type disclosed in my co-pending applications Serial No. 309,853, filed July 10, 1919; Serial No. 374,276, filed April 13, 1920; and Serial No. 381,466, filed May 14, 1920.

In said applications I have set forth an electric switch having a resiliently supported oil receptacle and a switch frame forming a cover for said receptacle having a peripheral flange or apron depending downwardly over the side wall of the receptacle and closely spaced therefrom to provide a narrow passage, although of comparatively great total area, down which vaporized liquid and gases will pass into a spill receptacle.

The object of this invention is to provide a switch of the above type with a plurality of gas channels formed by providing a plurality of projections, as ribs, or the equivalent on the inner face of said apron with relatively large passages therebetween adapted to engage and support the wall of the movably mounted oil receptacle when pressure is generated within the switch, as upon circuit interruption and the side-walls of the receptacle are forced outwardly; over which the oil receptacle is adapted to move as it yields downwardly due to the pressure.

The total surface of the ribs in engagement with the side-walls of the receptacle is adapted to be relatively small so that but little frictional resistance will be offered to oppose movement of the receptacle, even with a considerable pressure acting to force the side-wall against the ribs; and the spacing of the ribs is adapted to be such that ample area is provided therebetween for the expulsion of liquid and vapor, yet the ribs or other projections are adapted to be sufficiently closely spaced to support the side wall and prevent it from being forced into and close the passages.

Fig. 1 is a side elevation, partly in sec-

tion, of a switch incorporating my invention.

Fig. 2 is a plan sectional detail along line 2-2 of Fig. 1.

Fig. 3 is a sectional elevation of the switch of Fig. 1.

Fig. 4 is a sectional detail illustrating the relative position of the oil receptacle, and switch frame in a depressed position of the oil receptacle.

As here shown, the switch embodying my invention includes the switch frame 10 having the extended arm 11 by which the switch is fixed to a support. Stationary and movable switch members 12 and 13 are carried by said switch frame and depend therebelow and switch operating mechanism 14 is also carried by said frame.

The switch frame is formed with the peripheral depending flange or apron 15 which is adapted to enclose the oil receptacle 16 and depend a considerable distance down the side wall thereof whereby downwardly to guide oil and vapor expelled from the switch upon circuit interruption.

Said oil receptacle 16 is received within and supported by an outer receptacle or spill tank 17, the side-walls of which are relatively closely peripherally spaced from the side-walls of the oil receptacle whereby to provide a relatively narrow and long chamber adapted to receive the oil and vapor expelled from the switch and condense the condensable vapor and collect and retain it and the oil. The side-walls of said spill receptacle preferably extend upwardly beyond the lower end of said apron 15 whereby practically all of the oil and vapor will be directed into the receptacle; and the side-walls are relatively closely spaced from said apron whereby to provide a relatively narrow passage which, while of ample area freely to permit the discharge of uncondensed vapor and gas from the receptacle, will, in combination with the shape of the chamber between the two receptacles, prevent the maintenance of combustion therein.

Said outer receptacle rests upon the grids 18, or it may be one grid, which extend laterally beyond the side walls of the receptacle; and the extended end-portions are provided with apertures. Rods 19 are received in said apertures and are fixed to said grids. Said rods extend upwardly on

opposite sides of the outer receptacle and through apertures in extended lugs 20 of the switch frame. The upper end-portions of said apertures are enlarged to form the 5 spring-receiving recesses 21 and compression springs 22 are received in said recesses and encircle said rods. The upper end-portions are threaded and nuts 23 are removably threaded thereon and engage the upper 10 end of said springs whereby a yielding support for the oil receptacle is provided. The oil receptacles may be removed from the switch frame by removing said nuts.

Ordinarily said springs are adapted 15 yieldingly to hold the top of the oil receptacle 16 directly in contact with the under side of the switch frame and yield, under influence of pressure within the switch, to permit the receptacle to move away from 20 the switch frame whereby to provide a relatively large opening for the expulsion of oil and gas or vapor. Normally the switch will be what is termed "non-vented" yet, due to irregularities of contact between the top 25 of the oil receptacle and the switch frame, sufficient clearance space will be formed therebetween to enable the switch to breathe.

For some purposes, however, it may be desirable to provide a definite passage of 30 substantial height between the top of the receptacle and the switch frame so that the switch will be at all times in substantially unrestricted communication with the atmosphere, or freely vented. This result may be 35 accomplished by limiting the extent of upward movement of the oil receptacle under influence of said springs by suitable means, as by the sleeves 24 fixed to said rods 19 beneath said lugs 20 and so disposed thereon 40 as to engage the bottom of said lugs and limit further upward movement of the receptacle.

Oil and gas and vapor expelled from the switch as during circuit interruption and 45 when the oil receptacle moves downwardly is adapted to pass over the top of the oil receptacle and downward between the side-walls of said receptacle and said apron 15 into the outer or spill receptacle.

Considerable pressure may be set up 50 within the switch, upon certain conditions of circuit interruption, and the pressure may be sufficient to distort the oil receptacle and force its side-walls against said apron 55 15 sufficiently strongly to prevent the proper yielding or downward movement of the receptacle; and also may materially reduce the effective area of the vent passage between the receptacle and apron. For this reason 60 means are provided whereby the extent of contact between the side-walls and the apron will be small and the walls of the receptacle

will be supported by the apron at numerous points. Said means specifically comprises the plurality of vertically disposed ribs 25 65 integrally formed on the inner face of said apron 15, and extended therebeyond adapted to engage and support the side wall of the oil receptacle 16. Said ribs preferably extend vertically the length of the apron 70 whereby the greatest support for the walls of the oil receptacle is provided. The width of said ribs is relatively small whereby but small surface is presented to oppose movement of the oil receptacle. A relatively 75 large number of ribs are provided whereby the receptacle will be supported at numerous points; and the spaces *a* between the ribs provide passages for gas and oil expelled from the switch, the total area of which is 80 relatively large. The spacing of the ribs is sufficiently close to support the walls of the oil receptacle against appreciable bulging into the spaces *a*.

I claim:

1. An electric switch comprising a switch frame and an oil receptacle movably supported relative to said frame; said frame having a peripheral apron depending therefrom surrounding and peripherally spaced from the upper portion of said oil receptacle and having a plurality of supporting projections extended from its inner face to engage and support the side walls of said oil receptacle and provide a vent passage between said receptacle and frame in moved positions of the oil receptacle. 90 95

2. An electric switch comprising a switch frame and an oil receptacle movably supported relative to said frame, said frame having a peripheral apron depending therefrom surrounding and peripherally spaced from the upper portion of said oil receptacle having a plurality of vertically-extended channels in its inner face to provide vent 100 105 passages between the side walls of said receptacle and said apron.

3. An electric switch comprising a switch frame and an oil receptacle movably supported relative to said frame, said frame having a peripheral apron depending therefrom surrounding and peripherally spaced from the upper portion of said oil receptacle having a plurality of supporting projections of relatively small surface area extended from its inner face to engage and support the side walls of said oil receptacle and provide and maintain a vent passage between the side walls of said receptacle and said apron in moved positions of said receptacle. 110 115 120

In testimony whereof, I have signed my name to this specification.

GEORGE A. BURNHAM.
